RAILWAY TRAFFIC CONTROLLING APPARATUS

Earl M. Alien, Swissvale, and Thomas J. O'Meara, Pittsburgh, Pa., assignors to The Union Switch & Signal Company, Swissvale, Pa., a corporation of Pennsylvania

Application September 5, 1935, Serial No. 39,306

12 Claims. (Cl. 246—136)

Our invention relates to railway traffic controlling apparatus, and particularly to apparatus wherein a switch and the signals governing traffic thereover are controlled by manually operable levers.

More specifically our invention relates to means for locking the switch lever in one position or another, and to means for insuring that the locking means is in the locking position before the signals associated with the switch can be caused to indicate proceed.

We will describe two forms of apparatus embodying our invention, and will then point out the novel features thereof in claims.

15 In the accompanying drawings, Fig. 1 is a diagrammatic view illustrating one form of apparatus embodying our invention wherein the switch is electrically controlled by the switch lever. Fig. 2 is a diagrammatic view illustrating another form of apparatus also embodying our invention wherein the switch is mechanically controlled by the switch lever.

Similar reference characters refer to similar parts in each of the views.

25 Referring to Fig. 1, the reference character A designates a railway switch for connecting a siding or a branch track E with a main track F. This switch is operated by a mechanism M, which is controlled by a polarized switch control relay WR, this relay in turn being governed by a manually operable lever L1.

The movements of cars and trains through the switch A are governed by suitable signals, each of which is designated by the reference character S with a suitable distinguishing prefix. These signals are governed by a manually operable signal lever designated by the reference character L2.

30 The levers L1 and L2 are interconnected by suitable mechanical interlocking apparatus J as will hereinafter be explained.

The tracks E and F adjacent to the switch A are provided with a track circuit comprising the usual track battery 2, the rails of the tracks, and a track relay TR. The insulated joints 3 separate the rails of the track circuit from the adjacent track rails. The track relay TR is utilized in such manner, as hereinafter will be explained, that the switch lever L1 cannot be manipulated if the track circuit is occupied by a train.

35 Associated with the signals S is a pair of approach locking relays designated by the reference characters RMR and LMR. In order to simplify the drawings, no control circuits are shown for the approach locking relays. It is understood that

these relays function in the usual and well-known manner. That is, relay RMR becomes deenergized when signal S1 or signal S2 is cleared to permit movements of traffic from left to right over the switch A, and relay LMR becomes deenergized when signal S3 or signal S4 is cleared to permit movements of traffic from right to left over the switch A. When either approach locking relay is deenergized, the switch lever L1 is locked, as will be explained hereinafter, so that the switch 10 cannot be operated.

The lever L1 comprises an arm 4 pivotally mounted at the point 6. The arm 4 is locked in normal and reverse positions by means of a dog 7 cooperating with a quadrant 8. The dog 7 is arranged to be elevated by a latch handle 5 pivotally mounted on the lever arm 4 and operatively connected with the dog by a latch rod 9. When the lever arm 4 is in the normal position, as shown in the drawings, dog 7 is at the right-hand end of the quadrant 8, and when the lever arm is in the opposite or reverse position, the dog is at the left-hand end of the quadrant. The dog 7 is arranged to slide in a rocker link 10, which is pivotally mounted at the point 11. The center of curvature of the quadrant 8 is at point 6 and the center of curvature of the slot in rocker link 10 when this link is in its middle position is at the same point. It will be seen, therefore, that when latch handle 5 is operated to elevate dog 7, the rocker link 10 will swing through one-half of its angular movement, that when the lever arm 4 is shifted to its reverse position the rocker link 10 will remain at rest, and that when the latch handle 5 is released to permit dog 7 to drop into its reverse locking position, the rocker link will swing through the other half of its angular movement.

40 Operatively connected with the rocker link 10 is a segment 12 which cooperates with a dog 13 controlled by an electromagnet 14 through the medium of an armature 15. These elements constitute a means for holding the rocker link 10 in either of its extreme positions or in its intermediate position until the magnet 14 becomes energized. That is, the rocker link 10 cannot be moved from its normal or its reverse position unless the magnet 14 is energized and when rocker link 10 is moved to its intermediate position, further movement of the rocker link 10 is prevented unless magnet 14 is energized. The armature 15 and dog 13 are provided with a contact 16 which is closed only when the dog 13 is in the locking position.

45 Although the armature 15 of the magnet 14 50

is here shown as being biased to a normal de-energized position by gravity, it is understood that this armature may be so biased by other means such, for example, as by a spring or as by movement of the segment 12 itself.

When the segment 12 is operated from its normal to its reverse position, the segment passes through successive positions relative to dog 13 as indicated by the reference characters N, X, B, C, D, Y and R disposed adjacent the segment. That is, when rocker link 10 is moved to its intermediate position, segment 12 moves from position N, through positions X and B in succession, to position C. When the lever arm 4 is reversed, rocker link 10 and segment 12 remain stationary. When rocker link 10 completes its movement to its reverse position, segment 12 moves from position C, through positions D and Y in succession, to position R. When rocker link 10 and segment 12 are moved in the opposite direction, the segment 12 moves through these positions in their reverse order.

The segment 12 controls movable contacts 17, 18, 19, 20 and 21 which engage with fixed contacts in accordance with the positions of segment 12 relative to dog 13 as designated by the reference characters disposed adjacent the fixed contacts. For example, when segment 12 is at position N or position X or at any point between positions N and X, movable contact 17 is in engagement with fixed contact N—X.

Segment 12, by means of movable contacts 20 and 21, controls polarized switch control relay WR in accordance with the positions of the segment. That is, when segment 12 is in its normal position, relay WR is energized in the normal direction over easily traced circuits, and when segment 12 is in its reverse position, relay WR is energized in the reverse direction. Mechanism M is provided with easily traced circuits controlled by relay WR in the well-known manner. That is, when relay WR is energized in the normal direction, mechanism M is caused to operate the switch A to its normal position and when relay WR is energized in the reverse direction, the mechanism M is caused to operate the switch A to its reverse position.

Associated with the switch is a polarized indication relay KR which is controlled by movable pole-changing contacts 22 and 23 which contacts are controlled by any usual and well-known means in accordance with the switch position. The relay KR is provided with an easily traced control circuit which is closed, as hereinafter will be explained more in detail, when contact 16 is closed or when movable contact 19 is in engagement with fixed contact B—D. That is, the control circuit for relay KR is closed when magnet 14 is deenergized or when segment 12 is in its intermediate position.

The signals S1, S2, S3 and S4 are controlled by easily traced circuits which include a front contact of the track relay TR, contacts of the switch indication relay KR and a contact controlled by the signal lever L2. For example, signal S1 is controlled by a circuit which passes from terminal P of a suitable source of energy, through front contact 30 of track relay TR, front contact 31 of switch indication relay KR, right-hand contact 32—33 of lever L2, normal polar contact 34—35 of relay KR, and signal S1 to terminal O of the same source of current. Signal S1, therefore, can be caused to indicate proceed only if the track relay TR is energized and then only if the indication relay KR is energized in

the normal direction. Since the relay KR can be energized only if the magnet 14 is deenergized when the segment 12 occupies one or the other of its extreme positions, it is readily apparent that signal S1 cannot be caused to indicate proceed unless the segment 12 is locked in its normal position. 5

The mechanical locking J between the levers L1 and L2 is so arranged that lever L2 cannot be moved from its normal position, as shown in 10 the drawings, unless rocker link 10 occupies one or the other of its extreme positions, and when lever L2 is manipulated, either to the right or the left, rocker link 10 is locked in such extreme position. 15

The electromagnet 14 is provided with two control circuits each having two branch paths. The first control circuit passes from terminal P through front contact 30 of relay TR, front contact 35 of approach locking relay RMR, front contact 37 of approach locking relay LMR, floor push circuit controller 38, and thence through two paths, the first of which passes through fixed contact N—X, movable contact 17 and magnet 14 to terminal O, and the second of which passes 25 through fixed contact R—Y, movable contact 17 and magnet 14 to terminal O. The second control circuit includes the same path as just traced for the first circuit up to and including floor push circuit controller 38, and thence through two 30 branch paths both of which include front contact 39 of relay KR, the first path also including normal polar contact 40—41 of relay KR and fixed contact N—B in engagement with movable contact 13, and the second path including reverse 35 polar contact 40—42 of relay KR and fixed contact R—D in engagement with movable contact 13. Magnet 14 therefore can be energized when segment 12 is in either extreme position, if relays 40 TR, RMR and LMR are all energized, and can be energized when segment 12 is in its intermediate position, if relays TR, RMR, LMR and KR are all energized provided that the condition of relay KR agrees with the condition of segment 12. Thus, magnet 14 and dog 13 cooperating with 45 segment 12 provide switch lever L1 with detector locking and with indication locking. That is, lever L1 cannot be moved from either of its extreme positions if traffic conditions are such as to make such movement unsafe and lever L1 cannot 50 be moved from its intermediate position unless the switch and lever occupy corresponding positions.

Having thus described the various parts of the apparatus illustrated in Fig. 1, we will now 55 explain their operation.

We shall assume that with all apparatus in the normal condition as shown in the drawings, the operator desires to reverse switch A. Before latch handle 5 of lever L1 can be depressed to 60 release lever handle 4, magnet 14 must be energized. The operator, therefore, depresses floor push circuit controller 38 to energize magnet 14 by virtue of the previously traced control circuit for magnet 14 which circuit includes movable 65 contact 17 and fixed contact N—X. When magnet 14 is energized, segment 12 becomes unlocked so that latch handle 5 can be depressed to unlatch lever handle 4. When lever handle 4 is unlatched, the operator moves the lever handle to its reverse 70 position and releases latch handle 5 which moves segment 12 to the "D" or reverse indication position. The movement of segment 12 to the "D" position causes switch control relay WR to become energized in the reverse direction which 75

relay in turn energizes mechanism M in the reverse direction. When switch A has moved to its reverse position, the relay KR is energized in the reverse direction over a circuit which includes switch indication contacts 22 and 23 and movable contact 19 in engagement with fixed contact B—D. Relay KR, therefore, shifts its polar contacts to the right-hand or reverse position to energize magnet 14 by virtue of the previously traced control circuit which includes movable contact 18 in engagement with fixed contact RD. When magnet 14 is energized, dog 13 is raised clear of segment 12 so that the segment and rocker link 10 are free to move to the reverse position.

It will be noted that the magnet 14 cannot be energized to permit the final movement of segment 12 unless relay KR is energized in a direction corresponding to the position of the segment 12.

It will also be noted that when segment 12 moves from the "D" position, movable contact 19 is no longer in engagement with fixed contact B—D so that the relay KR becomes deenergized. As soon as the operator permits floor push circuit controller 38 to become opened, the magnet 14 becomes deenergized so that contact 16 becomes closed to reestablish the control circuit for the relay KR. When the relay KR is energized, the operator will manipulate signal lever L2 so as to clear the proper signal for permitting train movements over the switch A in the reverse position.

The operation of the apparatus for causing switch A to return to its normal position will be understood without further explanation.

Referring now to Fig. 2, the reference character A designates a railway switch which is mechanically operated by the switch lever L1 by means of the usual pipe line and cranks designated in general by the reference character Q.

The switch is provided with the well-known facing point lock bar 50 which moves with the switch and which is locked by plunger lock 51 entering normal recess 52 when the switch occupies its normal position and by plunger lock 51 entering reverse recess 53 when the switch occupies its reverse position.

Plunger lock 51 is operated by facing point lock lever L3 by means of the usual and well-known pipe line and cranks designated in general by the reference character T, so that when lever L3 is in its reverse position the switch A is locked in one of its extreme positions.

Lever L3 is similar in all respects to switch lever L1 and is provided with a segment 12A operatively connected to rocker link 10A. Segment 12A cooperates with dog 13 in such manner, that unless magnet 14 is energized, segment 12A is prevented from moving to and from its reverse position.

Plunger lock 51 operates contacts 54 and 55 in accordance with the position of the plunger lock by any usual and well-known means. That is, contacts 54 and 55 are closed when and only when the plunger lock 51 is in the locking position; that is, when lever L3 occupies its reverse position.

Switch lever L1 operates movable contact 56 in accordance with the lever position by any usual and well-known means. That is, movable contact 56 is in engagement with fixed contact 57 only when the lever occupies its normal position and is in engagement with fixed contact 58 only when the lever occupies its reverse position.

Magnet 14 is provided with a control circuit which passes from terminal P through front contact 30 of relay TR, front contact 36 of relay RMR, front contact 37 of relay LMR, floor push circuit controller 38, and thence through either of two paths one of which passes through normal polar contact 40—41 of relay KR, normal contact 56—57 of lever L1 and magnet 14 to terminal O and the other of which passes through reverse polar contact 40—42 of relay KR, reverse contact 56—58 of lever L1 and magnet 14 to terminal O. The magnet 14, therefore, can be energized only if relays TR, RMR and LMR are all energized and then only if the position of the polar contacts of relay KR correspond to the position of the contacts operated by lever L1.

The switch indication relay KR is provided with a circuit which includes switch indication contacts 22 and 23 and which further includes plunger lock contacts 54 and 55 as well as contact 16 which is closed only when magnet 14 is deenergized. That is, the relay KR will be energized in the normal or reverse direction in accordance with the switch position if and only if the switch is locked by lever L3 and then only if locking dog 13 occupies its locking position.

The mechanical locking JA between the levers L1, L2 and L3 is so arranged that latch handle 5A of lever handle 4A must occupy its reverse position before signal lever L2 can be manipulated. When facing point lock lever L3 is reversed so that latch handle 5A occupies its reverse position, switch lever latch handle 5 is locked in one or the other of its extreme positions, and when signal lever L2 is manipulated, latch handle 5A is locked in its reverse position.

Having thus described the various parts illustrated in Fig. 2, we will now explain their operation.

We shall assume that with all parts in the normal condition as shown in the drawings, it is desired to move and lock switch A in its reverse position. The operator may accomplish this by depressing latch handle 5 of lever L1, moving lever handle 4 to its reverse position and then releasing latch handle 5 so that lever handle 4 is latched in its reverse position. The movement of lever L1 to its reverse position drives switch A to its reverse position.

The operator now depresses latch handle 5A of lever handle 4A so that latch rod 9A elevates dog 7A out of engagement with quadrant 8A. The elevation of dog 7A moves rocker link 10A to its intermediate position which in turn drives segment 12A to its position "C" relative to dog 13. Lever handle 4A is now moved to its reverse position which drives plunger lock 51 into reverse recess 53 and also causes contacts 54 and 55 to become closed. When contacts 54 and 55 are closed, relay KR becomes energized in the reverse direction over switch indication contacts 22 and 23 which are now occupying their reverse position.

The operator now energizes magnet 14 by closing floor push circuit controller 38 so that dog 13 will move out of the path of segment 12A. When latch handle 5A is released, rocker link and segment 12A will complete their movement to their reverse position which will release the mechanical locking JA so that signal lever L2 can be manipulated.

When the floor push circuit controller is allowed to open, the magnet 14 will become deenergized so that contact 16 will become closed so as to establish the control circuit for the switch

indication relay KR. When relay KR is energized, its front contact 31 will become closed so that the proper signal may be caused to indicate proceed.

- 5 It will be noted that the facing point lock lever L3 may be unlatched and moved to its reverse position when the switch is in one or the other of its extreme positions but that the latch handle 5A is prevented from moving to its reverse position by the dog 13 unless the position of the polar contacts of the relay KR are in agreement with the position of the switch lever L2. Thus, latch handle 5A cannot complete its movement to the reverse position so that the 10 mechanical locking may release signal lever L2, unless the switch, the switch indicating relay and switch lever are all in corresponding positions.

From the foregoing, it will be apparent that 20 the apparatus embodying our invention provides a single and reliable means for insuring that an electric lock controlling a switch lever is in the locking position before any signal can be caused to indicate proceed to permit a train to pass over the switch.

Although we have herein shown and described 30 only a few forms of apparatus embodying our invention, it is understood that various changes and modifications may be made therein within the scope of the appended claims without departing from the spirit and scope of our invention.

Having thus described our invention, what we claim is:

35 1. In combination, a section of railway track having a railway traffic controlling device associated therewith, a polarized relay for indicating the condition of said traffic controlling device, manually controlled means for governing said traffic controlling device, a locking device controlled by traffic conditions in said section and by said polarized relay for locking said manually controlled means, and means controlled by said locking device for governing said polarized relay.

40 2. In combination, a section of railway track having a railway traffic controlling device associated therewith, a polarized relay for indicating the condition of said traffic controlling device, manually controlled means for governing said traffic controlling device, a locking device controlled by traffic conditions in said section and by said polarized relay for locking said manually controlled means, means controlled by said locking device for governing said polarized relay, and a signal for governing traffic in said section controlled by said polarized relay.

45 3. In combination, a section of railway track provided with a track circuit and a track relay, a railway traffic controlling device for said section, manually controlled means for governing said traffic controlling device, a polarized relay for indicating the condition of said traffic controlling device, a locking device for said manually controlled means governed by said track relay and by said polarized relay, and means controlled by said locking device for governing said polarized relay.

50 4. In combination, a section of railway track having a railway traffic controlling device associated therewith, an approach locking relay controlled by traffic approaching said section, a polarized indication relay for said traffic controlling device, manually controlled means for governing said traffic controlling device, a locking device

for said manually controlled means, means controlled by said approach locking relay and by said indication relay for governing said locking device, and means controlled by said locking device for governing said indication relay.

5 5. In combination, a section of railway track, a switch associated with said section and having normal and reverse positions, a lever for controlling said switch having two extreme positions corresponding to the positions of the switch, a locking device for said lever and having a locked and unlocked condition, traffic controlled means associated with said section effective to prevent the device from assuming its unlocked condition when the section is occupied by a train, an indication relay for said switch, and means for energizing said indication relay in the normal or reverse direction according as said switch is in its normal or reverse position effective when said lever is in its extreme positions if and only if said locking device is in its locked condition.

10 6. Railway traffic controlling apparatus comprising a lever having normal and reverse positions, electrically controlled means for holding said lever in its normal and reverse positions and for releasing said lever when said means is energized, a railway switch having normal and reverse positions, an indication relay associated with said switch, means for energizing said indication relay in a normal or reverse direction according as the switch occupies its normal or reverse position effective when said lever is in its normal or reverse positions if and only if said lever holding means is in its holding position, means for controlling said railway switch by said lever, and means for energizing said lever holding means.

15 7. Railway traffic controlling apparatus comprising a lever having two extreme positions and an intermediate position, an electric lock effective when deenergized to lock said lever in its intermediate position and effective when energized to release said lever, a railway switch, an indication relay controlled by said switch and by said electric lock, a circuit including a contact of said indication relay for energizing said electric lock when said lever is in its intermediate position, and means for controlling said railway switch by said lever.

20 8. Railway traffic controlling apparatus comprising a lever having normal and reverse positions, electrically controlled means for holding said lever in its reverse position and for releasing said lever when energized, a railway switch having normal and reverse positions, an indication relay associated with said switch, means for energizing said indication relay in the normal or reverse direction according as the switch is in its normal or reverse position effective when said lever holding means is in its holding position and said lever is reversed, means for locking said railway switch in its normal and reverse positions effective when said lever is reversed, and means for energizing said lever holding means.

25 9. Railway traffic controlling apparatus comprising a first lever having normal and reverse positions, an electric lock effective when deenergized to prevent said first lever from assuming its reverse position and effective when energized to release said lever, a railway switch having a normal and a reverse position, an indication relay controlled by said electric lock and by said switch and having a contact which assumes a normal or a reverse position depending upon the position of said switch, a second lever having a normal and

reverse position for controlling said switch, means including said indication relay contact for energizing said electric lock effective when said second lever and said contact occupy corresponding positions, and means for locking said railway switch in its normal and its reverse position effective when said first lever is reversed.

10. Railway traffic controlling apparatus comprising a switch lever having normal and reverse positions, a latch associated with said switch lever and having a normal position in which said switch lever is latched in its normal position and an intermediate position in which said switch lever is not latched as well as a reverse position in which 15 said switch lever is latched in its reverse position, an electric lock for locking said latch in its normal and reverse positions as well as in its intermediate position, a railway switch, an indication relay associated with said switch, means 20 for controlling said indication relay effective both when said electric lock is in the locking position and also when said latch is in the intermediate position, a signal lever controlled by said switch lever, a signal controlled jointly by said indication relay and by said signal lever, and latch 25 controlled means for unlocking said electric lock.

11. Railway traffic controlling apparatus comprising a lever having two extreme positions as well as an intermediate position, an electric lock 30 for locking said lever in its normal and reverse

positions as well as in its intermediate position, means including contacts actuated by said lever for controlling said electric lock, a railway switch controlled by said lever, an indication relay associated with said switch, means including a contact of said electric lock for energizing said indication relay when and only when said electric lock is in its locking position if said lever is then in one or the other of its extreme positions, and a signal for governing movement of traffic over 10 said switch and controlled in such manner that said lever must be in one of its extreme positions and said indication relay must be energized before said signal can be caused to indicate proceed.

12. In combination, a section of railway track, 15 a switch and a signal associated with said section, a lever for controlling said switch, a locking device for said lever effective to lock said lever in its extreme positions as well as in its intermediate position, means controlled by traffic conditions in said section for unlocking said locking device, a contact closed only when said locking device is in its locking condition, an indication relay controlled by said switch and energized only when 20 said contact is closed, and means for clearing said signal when and only when said indication relay is energized.

EARL M. ALLEN.

THOMAS J. O'MEARA. 30
